UNITED STATES PATENT OFFICE

2,092,935

FLOAT VALVE

Albert C. Smith, Evansville, Ind., assignor, by
mesne assignments, to Servel, Inc., Dover, Del.,
a corporation of Delaware

Application October 1, 1934, Serial No. 746,331

6 Claims. (Cl. 137—104)

My invention relates to refrigeration and more particularly to an absorption type refrigerator operated by a liquid fuel burner.

It is an object of my invention to provide a refrigerator of this type having a temperature adjustment means accessible to the user.

Another object is to provide a liquid fuel burner for an absorption type refrigerator having an adjustment means which is simple and accurate.

10 I attain these objects by utilizing a liquid fuel burner regulated by a float valve for heating a generator of an absorption type refrigerator, and provide for gradual adjustment of the burner flame and, thereby, the refrigeration temperature, 15 by fine adjustment of the float valve operation. I may do this, for instance, by adjustably weighting the burner float with a flexible weight element such as a chain which I herein generically term a weight string. My invention will be more 20 fully understood upon consideration of the following description and the accompanying drawings forming part of this specification and of which:

Fig. 1 is a broken side elevation, with parts 25 broken away, of a refrigerator embodying my invention; and

Fig. 2 is a detail view, partly in vertical section, of a liquid fuel burner for the refrigerator shown in Fig. 1.

30 Referring to Fig. 1 of the drawings, a refrigerator cabinet 10, itself of known construction, includes a thermally insulated storage compartment 11 accessible by means of a door 12, and a lower apparatus compartment 13 accessible by 35 means of a downwardly opening, hinged door 14 or other suitable closure member. An absorption refrigeration apparatus which may be of the general type disclosed in Patent 1,609,334 to Von Platen, et al., is mounted in the cabinet 10 and 40 includes a cooling element or evaporator 15 in the storage compartment 11 and a generator having a substantially horizontal portion 16 in one side of the lower apparatus compartment 13.

The horizontal portion 16 of the generator is 45 provided with a substantially horizontal inner heating flue 17 extending therethrough and is surrounded by an outer heating flue 18. The latter is surrounded by suitable thermal insulating material 19, such as mineral wool, retained 50 in place by a light sheet metal casing 20. The forward end of the heating flue 18 projects beyond the front end of the casing 20 and also beyond the end of the inner heating flue 17. Beneath the forwardly projecting end of the outer 5 heating flue 18 is mounted a liquid fuel burner

assembly 21 having a removable chimney or combustion shield 22 which extends upwardly into the forwardly projecting end of the outer heating flue 18 which is provided with a cutaway portion or recess 23 to admit the upper end of the chimney 22. The forwardly projecting end of the flue 18 and the upper end of the burner chimney 22 are enclosed by a removable thermally insulated hood 24. For a more complete description of this assembly, reference may be had to an application Serial No. 734,075 of William R. Hainsworth.

In the other side of the lower apparatus compartment 13 is a storage tank or reservoir 25 for liquid fuel, such as kerosene. Liquid is conducted from the reservoir 25 to the burner 21 through a conduit 26.

The construction of the burner 21 may be best understood by reference to the detail section in Fig. 2. The burner assembly includes a safety valve 27, a float valve 28, a float chamber 29, a burner tube 30, an annular burner well 31, and the removable chimney 22. Liquid fuel flowing to the burner through conduit 26 passes through the normally open safety valve 27 and a conduit 33 into a valve chamber 34. Flow of liquid fuel from the chamber 34 into the float chamber 29 is regulated by the float valve 28 to maintain a substantially constant level of liquid in the float chamber. The float chamber 29 includes a portion formed by a float vessel 35 in which is contained a suitable float 36. The float 36 is operatively connected to the valve 28 by means of a rod or valve stem 37. The float 36 may be provided with a recess 38 in the top thereof for a purpose which will hereinafter appear. The float vessel 35 is provided with a suitable cover 39 having an opening 40 in the top thereof, over the recess 38 in the float 36. Liquid flows from the float chamber 29 toward the annular burner well 31 through the burner tube 30 and stands in the burner tube 30 substantially at the same level as that in the float chamber. The chimney 22 which is removably supported above the burner well 31 comprises a pair of perforated concentric cylinders 41 and 42, forming an annular combustion space above the annular burner well 31, and an outer shield or chimney comprising a frustoconical shell 43. The cylinders 41 and 42 and the chimney 43 are retained in their assembled positions by perpendicular bars 44 and pins 45.

The float 36 and valve 28 are constructed to normally maintain a substantially constant level of liquid in the float chamber 29 and the burner tube 30, for instance, at the level L. At this level the burner produces a relatively small flame,

herein referred to as the minimum flame. It will be understood that the burner flame and, therefore, the heat produced by the burner may be increased by raising the level of liquid in the burner tube 30.

In accordance with my invention, I provide a suitable weight string such as a chain 46. Referring to both Figs. 1 and 2 of the drawings, the chain 46 is suspended over pulleys 47 and 48. The pulley 47 is located over the opening 40 in the float vessel cover 39 so that one end of the chain may depend through the opening 40 directly above the recess 38 in the float 36. The pulley 48 is located over a spindle or stub shaft 49 so that the other end of the chain 46 may be secured to the stub shaft in such a manner as to become wound and unwound upon turning of the shaft in opposite directions. The shaft 49 may be suitably journaled in the front of a shield plate 50 which laterally surrounds the burner assembly 21. A suitable knob 51 is provided for turning the shaft 49 to wind and unwind the chain 46. The stub shaft 49 may be extended through the front of the shield 50 and the knob 51 secured on the end of the shaft outside of the shield so as to be readily accessible from the front of the refrigerator, as illustrated.

It will now be understood that turning the knob 51 to unwind the chain 46 allows the other end of the chain to descend into the recess 38 in the top of the float 36 and add its weight to that of the float. If the weight of that portion of the chain 46 below the pulley 47 is not sufficient to carry the weight of the chain between the pulleys 47 and 48, a weight W may be added to the chain 46 below the pulley 47 to insure deposit of the chain upon the float 36 upon unwinding of the chain when the knob 51 is turned. The additional weight of that portion of the chain 46 resting upon the float 36 results in a greater displacement and a sinking of the float, and a higher level of liquid in the float chamber 29 is necessary to raise the float sufficiently to close the valve 28. A higher liquid level is therefore maintained in the float chamber and burner tube 30 and a correspondingly greater burner flame is produced.

By suitably providing one or more stops 52 for the knob 51, the amount of chain deposited upon the float 36 may be limited to that required for producing the desired maximum flame which results when the liquid level is at some higher level such as that indicated by the level line H. By turning the knob 51 intermediate the stop or stops 52, the liquid level in the burner tube and therefore the burner flame may be adjusted between its maximum and minimum values. Since the temperature of the refrigerator cooling element 15 may be changed by changing the heating of the generator 16, adjustment of the burner 60 flame by turning the knob 51 results in adjust-

ment of the refrigerator temperature. The knob 51 may therefore be referred to as a temperature adjustment.

Various changes and modifications will be apparent to those skilled in the art, wherefore my invention is not limited to that which is shown in the drawings and described in the specification but only as indicated in the following claims.

What I claim is:

1. In a kerosene burner for absorption refrigeration apparatus, a float chamber, a valve for regulating flow of kerosene to said float chamber, a float in said chamber operatively connected to said valve, a weight string movable for deposit of variable length thereof on said float, and means 10 for moving said string.

2. In a kerosene burner for absorption refrigeration apparatus, a float chamber, a valve for regulating flow of kerosene to said float chamber, a float in said chamber operatively connected to said valve and having a recess in the top thereof, a weight string having one end depending into said recess and movable for deposit of variable length thereof therein, and means for moving said string. 20

3. In a kerosene burner for absorption refrigeration apparatus, a float chamber, a valve for regulating flow of kerosene to said float chamber, a float in said chamber operatively connected to said valve and having a recess in the top thereof, 30 a chain having one end depending into said recess and movable for deposit of variable length thereof therein, and means for moving said chain.

4. In a kerosene burner for absorption refrigeration apparatus, a float chamber, a valve for regulating flow of kerosene to said float chamber, a float in said chamber operatively connected to said valve and having a recess in the top thereof, 40 a chain having one end depending into said recess and movable for deposit of variable length thereof therein, and rotatable means connected to the other end of said chain for moving the latter.

5. A liquid fuel burner for absorption refrigeration apparatus and having regulating means including a float, and means for increasing and decreasing the weight of said float comprising a flexible member constructed and arranged to be deposited on said float in various amounts. 41

6. A liquid fuel burner for absorption refrigeration apparatus and having regulating means including a float, means for increasing and decreasing the weight of said float comprising a flexible member constructed and arranged to be deposited on said float in various amounts, and a rotatable member for manipulating said flexible member. 5

ALBERT C. SMITH. 6
